ISAAC SNOW, OF LAWRENCE, MASSACHUSETTS.

SHUTTLE.

Application filed April 20, 1925. Serial No. 24,370.

This invention relates to self-threading shuttles.

In an automatic loom when the bobbin is shifted, at the first pick it is desirable that 5 the yarn should automatically slip under a front hook and preferably also under a back hook or guide, and during the second pick should slip into the eye down in back of the horn and in front of the pin, and should stay 10 there.

However at the beginning of the second pick, there is a period when the yarn is slack and there is a tendency to kink. During this 15 period there is a tendency for the yarn to drop or slip out from under the front hook, and being kinked, to remain out during that pick, and to run over the top of the shuttle block.

When this happens, it is desirable to have a stop or guard to prevent the yarn from 20 slipping way back to the bobbin for if that happens the yarn must break.

I prefer to use for this stop, a back hook so shaped that it allows the yarn to slip down over its outside to its inner side and with a 25 long end which extends along parallel with and close to a thread rest as this makes a relatively large mouth or pocket to catch the escaped yarn.

The very shape of the back hook however 30 makes it possible for a loop of yarn to be thrown forward from the bobbin and to slip under and past the back hook and to get tangled up at the front. In such case, to catch the yarn, I use a front hook which extends down and back along parallel with and close to the thread rest forming a mouth or pocket to catch any such loop.

At the same time, the guide plate or wall 40 of the shuttle block of which both hooks are extensions must extend over and down into the thread recess in the direction of the path of the unwinding yarn so that the tendency is always for the yarn to thread and re-thread.

In the drawings, Fig. 1 is a plan view of a 45 shuttle with my improvement.

Fig. 2 is an elevation as from the top of Fig. 1 of the shuttle block removed from the shuttle.

Fig. 3 is a front view of the shuttle block 50 removed from the shuttle.

Fig. 4 is a back view of Fig. 3.

Fig. 5 is an elevation of the opposite side from Fig. 2.

Fig. 6 is a bottom view of the shuttle block.

Fig. 7 is a side elevation similar to Fig. 2 55 of a modified form of shuttle block.

Fig. 8 is a back view of Fig. 7.

Fig. 9 is a side elevation of another modified form of shuttle block.

Fig. 10 is a back view of Fig. 9.

S is a shuttle of the self-threading type 60 for automatic looms, having the usual bobbin chamber 10 for the bobbin B from which the thread A is unwound in the direction of the arrow in Fig. 1. 12 is the thread chamber 65 which extends forward in continuation of bobbin chamber 10, and 13 is the delivery passage which extends still further forward from the threading chamber.

H represents the shuttle eye in the wood, 70 and this connects with the threading chamber 12 through the slot 15 cut away from the delivery passage 13. 8 represents the metal tip of the shuttle.

This eye H is what is known as a left eye, 75 as it is at the left when looking towards the tip 8 of the shuttle.

F represents a metallic threading block 80 which is set into a recess 4 in the wood of the shuttle and is shown as fixed therein by means of a screw 36 which passes through a hole in the wood of the shuttle and a hole 35 in the block, in a well known manner. Preferably there is also at the bottom of block F, 85 the projection 34 which fits into a recess in the wood of the shuttle.

32 is the horn and 33 the thread pin, both of well known form.

My improvement is more particularly useful 90 in connection with a certain type of threading block in which there is a thread directing guide plate G which extends from the top thereof and from the top side of the shuttle, down and out at 22 into the threading chamber 12, or that part of the threading 95 chamber which is enclosed in the threading block itself indicated at 9 in Fig. 1.

In Figs. 1 to 5, there is at or near the back a thread retaining guide hook or member 28 which is in extension of the sloping part 22 100 of guide plate G. As this together with the part 22 of guide plate G extends in the same direction and proximate the normal unwinding path of the thread as it unwinds on the first pick of the shuttle in a magazine loom, 105 that is in the direction of the arrow in Fig. 4, it is clear that it will slip into the part 9 of the threading chamber 12.

This is provided that the axis of the bobbin 110 B somewhere nearly coincides with the bottom or axis of the passage 9 as should be the case and as shuttles are ordinarily constructed.

It is clear that when once in the passage 9, the unwinding thread will travel around in the direction of the arrow as it unwinds from the bobbin, and there will be very little likelihood of its unthreading even if there is no overlap locking device such as shown in certain other patents.

The guide plate or guide wall G which is shown as being part of or starting at the top 10 of shuttle block F, extends down in passage 9 as part of the outside edge of back hook 28 and of front hook 16. These hooks are in extension thereof.

I prefer to form on the other side of passage 9, that is the side opposite eye H, a thread rest 40, which preferably slopes down from the front end 41 to the back end 42.

I prefer to make the tip 27 of the back hook 28 relatively long and parallel with and 20 close to the top of thread rest 40, and in the same way to extend the tip 17 of front hook 16, parallel with and close to this top wall so that in each case there will be a very narrow passage for the thread to pass through.

25 As shown by the dotted line R, if the yarn escapes from the front it will be caught on the front side of hook 28 until on the next pick it will slide down around front hook 16 and re-thread.

30 On the other hand if the yarn A, instead of traveling in its natural course, should balloon or be thrown forward in a loop as shown by the dotted line T in Fig. 1, this loop will inevitably be caught by the front hook 16 and kept in place so that as soon as it is pulled by the movement of the shuttle, 35 it will slide back into its proper position.

Wall 5 of block recess 4 is preferably substantially vertical.

40 50 is a recess for a piece of felt or other friction device.

The front end 43 of thread rest 40 preferably curves around close to and under the long flat tip 17 of front hook 16 and the outer edge of tip 17 preferably slants from the front to the back towards eye H.

45 In Fig. 7, I show one way of making front and back hooks which may be used to advantage.

50 80 represents the guide wall of the shuttle block which extends down and over into the shuttle block recess, and 81 is the front hook in extension thereof, while 83 is the back hook. These can conveniently be formed by 55 casting, and then by boring out the metal as shown by the dotted circles, so as to form parts 81 and 83 into suitable hooks. The tips of these hooks, such as 86 and 87, can then be pointed.

60 The thread rest 85 slopes from the front 82 down to the back 84 and should be close to but not extending up between the front and the back hooks.

In Figs. 9 and 10, I show another modification, and also another way in which the

front and back hooks can be formed. 90 represents the guide wall and 93 the front hook, and 94 the back hook, while 91 represents the thread rest.

In this case the front and back hooks 93 70 and 94 may be cast in the form shown by the dotted lines, and then bent in to the full line position inside thread rest 91. The tip end of front hook 93 is slightly above and inside the thread rest while the end 95 of back hook 75 94 is inside and below the thread rest 91, which as shown extends down at a slant so as to form a sort of open mouth to receive the yarn as it slips in.

I also prefer to use a cylindrical piece of 80 felt 92 which passes through a hole 97 between the front and back hooks.

In Figs. 9 and 10, the thread rest is not bent around at the front as at 43, but is straight.

I claim:

1. The combination in an automatically threading shuttle having in one side an eye in the wood, a shuttle block recess having a substantially vertical side wall opposite said eye, a thread receiving slot which extends forwardly from said recess, and a passage connecting the eye with the recess; of a shuttle block fastened in said recess having at the top a guide wall which extends down into the recess away from the eye, and is formed at the 95 front with a flat front hook which extends down in towards the axis of the shuttle and back, and at the back with a flat back hook which extends down and forward, both in extension of the guide wall, said front hook and 100 said back hook serving as the sole thread retainers for preventing the escape of the thread from the thread chamber through the thread entrance to the threading chamber; and said thread rest which extends up in the recess opposite the eye along the vertical wall and which slopes around therefrom towards the eye, and down from the front to the back parallel with and just below the front hook and just below the back hook.

2. The combination in an automatically threading shuttle having on one side an eye in the wood, a shuttle block recess having a substantially vertical side wall opposite said eye, a thread receiving slot which extends forwardly from said recess, and a passage connecting the eye with the recess; of a shuttle block fastened in said recess having at the top a guide wall which extends down into the recess away from the eye, and is formed at the front with 115 a front hook which extends down in towards the axis of the shuttle and back, and at the back with a back hook which extends down and forward, both in extension of the guide wall; said front hook and said back hook 120 serving as the sole thread retainers for preventing the escape of the thread from the thread chamber through the thread entrance to the threading chamber.

3. The combination in an automatically 130

threading shuttle having in one side an eye in the wood, a shuttle block recess having a substantially vertical side wall opposite said eye, a thread receiving slot which extends for-
wardly from said recess, and a passage connecting the eye with the recess; of a shuttle block fastened in said recess having at the top a guide wall which extends down into the recess away from the eye, and is formed at the front with a flat front hook which extends down and back, and at the back with a flat back hook which extends down and forward, both in extension of the guide wall, said front hook and said back hook serving as the sole
thread retainers for preventing the escape of the thread from the thread chamber through the thread entrance to the threading chamber; and said thread rest which extends up in the recess opposite the eye along the vertical wall from a point proximate the back hook up and forward under the front hook and thence towards the shuttle eye.
4. The combination in an automatically threading shuttle having in one side an eye in the wood, a shuttle block recess having a substantially vertical side wall opposite said eye, a thread receiving slot which extends for-
wardly from said recess, and a passage connecting the eye with the recess; of a shuttle block fastened in said recess having at the top a guide wall which extends down into the recess away from the eye and is formed at the front with a nose which extends sharply downward and is extended around forming a bend at the front and bottom and thence back, into a flat front hook which extends down, in towards the axis of the shuttle and back, and is formed at the back with a flat back hook which extends down, and at its outer side in towards the axis of the shuttle and forward, both in extension of the guide wall, said front hook and said back hook serving as the sole thread retainers for preventing the escape of the thread from the thread chamber through the thread entrance to the threading chamber; and said thread rest which extends up in the recess opposite the eye along the vertical wall from a point proximate the back hook up and forward close to and under the back hook up to a point between the back tip and the bend at the front of the front hook and thence towards the shuttle eye.
